US0D1109462S

(12) **United States Design Patent** (10) **Patent No.:** **US D1,109,462 S**
(45) **Date of Patent:** **** Jan. 13, 2026**

(54) **MITE REMOVAL MACHINE**

(71) Applicant: **Suzhou BeiAng Smart Technology Co. Ltd.**, Suzhou (CN)

(72) Inventors: **Hongyu Ran**, Suzhou (CN); **Yan Zhang**, Suzhou (CN)

(73) Assignee: **Suxhou BeiAng Smart Technology Co. Ltd.**, Suzhou (CN)

(**) Term: **15 Years**

(21) Appl. No.: **29/877,706**

(22) Filed: **Jun. 11, 2023**

(30) **Foreign Application Priority Data**

Mar. 3, 2023 (CN) 202330090525.9

(51) **LOC (15) Cl.** **15-05**

(52) **U.S. Cl.**

USPC **D32/21**

CLAIM

The ornamental design for a mite removal machine, as shown and described.

DESCRIPTION

FIG. 1 is a front view of a mite removal machine showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof;

FIG. 8 is a second perspective view thereof; and,

FIG. 9 is a third perspective view thereof.
